UNITED STATES PATENT OFFICE.

HENRY J. BRESSON, OF KALAMAZOO, MICHIGAN.

GAS-STOVE.

No. 805,706.

Specification of Letters Patent.

Patented Nov. 28, 1905.

Application filed July 31, 1905. Serial No. 272,082.

To all whom it may concern:

Be it known that I, HENRY J. BRESSON, a citizen of the United States, residing at the city of Kalamazoo, county of Kalamazoo, State of Michigan, have invented certain new and useful Improvements in Gas-Stoves, of which the following is a specification.

This invention relates to improvements in gas-stoves. It relates particularly to gas-stoves for heating purposes, although it may be used as a cooking-stove.

The objects of this invention are, first, to provide an improved gas-stove which has a maximum heating capacity for the amount of gas consumed; second, to provide an improved gas-stove which is very simple and economical in structure embodying the above advantage.

Further objects and objects relating to structural details will definitely appear from the detailed description to follow.

I accomplish the objects of my invention by the devices and means described in the following specification. The invention is clearly defined, and pointed out in the claims.

25 A structure embodying the features of my invention is fully illustrated in the accompanying drawings, forming a part of this specification, in which—

Figure 1 is a vertical sectional view of my improved gas-stove, taken on a line corresponding to line 1 1 of Fig. 2. Fig. 2 is a horizontal sectional view taken on a line corresponding to line 2 2 of Fig. 1, showing structural details. Fig. 3 is a horizontal sectional view taken on a line corresponding to line 3 3 of Fig. 1, showing the means for supporting the burner and base-plate and the arrangement thereof. Fig. 4 is a detail vertical sectional view taken on a line corresponding to line 4 4 of Fig. 3. Fig. 5 is an enlarged sectional view taken on line 5 5 of Fig. 1, showing the structural details of the burner-tube.

In the drawings the sectional views are taken looking in the direction of the little arrows at the ends of the section-lines, and similar letters of reference refer to similar parts throughout the several views.

Referring to the drawings, A is the base, which is provided with suitable legs A', preferably formed integral therewith. The base is also provided with the cross-piece or bar A'', by which the bottom plate a and the burner are supported. The bottom plate a is preferably formed of sheet metal suitably perforated to admit air to the burner. The burner B is preferably formed like a funnel, with lat-

erally-opening jet-orifices b. The top of the burner is closed by the plate b'.

The burner-tube B' is elbow-shaped—that is, it is provided with a vertical portion—on the upper end of which is the burner B and a horizontal portion into which the gas-delivery nozzle is directed. The burner-tube B' is provided with a supporting-flange B''. (See Figs. 1 and 4.) This flange rests upon the base-plate, the tube being inserted therethrough. The cross-piece A'' is notched on one side to receive the tube, as clearly appears in Fig. 3. This enables the ready assembling of the parts.

The horizontal portion of the burner-tube 70 is cut away on its lower side at b'' to form an air-inlet. A sliding valve b''' is provided for controlling this air-inlet. This valve is formed of sheet metal and is conformed to engage the longitudinally arranged ribs b'''' on the 75 burner-tube, whereby it is adjustably retained in position. The delivery-nozzle F projects into the burner-tube to deliver thereto.

The base is provided with an upwardly-projecting flange a', adapted to receive the lower 80 end of the burner-casing c. The burner-casing is perforated to allow the free access of air to the burner. This casing is comparatively short and is open at its upper end.

A drum-like body is supported above the 85 burner-casing. The diameter of this body is greater than that of the burner-casing and extends somewhat below its upper end. The body preferably consists of the sheet-metal cylinder or barrel C, the top C', and the rim 90 C''. The top C' is provided with a downwardly-projecting flange c', on which the upper end of the barrel C is arranged. The rim C'' is provided with an upwardly-projecting flange c'', on which the lower end of the barrel C is arranged. These parts are secured 95 together and to the base by the standards or supports E. These standards are provided with suitable offsets, so that they fit within the drum and the burner-casing, as is illustrated. The standards are preferably secured to the flanges of the top C' and of the bottom rim C'' of the drum and to the flange a' of the base. I also preferably secure the same to the upper end of the burner-casing, as is 100 illustrated in Fig. 1. The parts are thus secured together and supported in proper relation in a simple and effective manner.

The top C' of the stove is preferably provided with a lid c''', so that the stove may, if 105 desired, be used for cooking purposes. I desire to remark, however, that the same is not

economical for use solely as a cooking-stove, as the top of the stove is so far removed from the burner. The stove is designed mainly for use as a heating-stove.

5 A removable cap D is provided to afford convenient access to the lid. This cap is provided with a suitable ornamental piece D'.

In use the heated air or gases pass upwardly into the drum and are forced out at the bottom thereof. This delivers the same close to the floor, and the downwardly-flaring rim C" gives them a downward direction. The heat is thus spread close to the floor. The drum or body becoming filled with the heated gases 15 throws out a considerable amount of heat by radiation. The drum may be comparatively large without in any way interfering with the burner, as the burner is surrounded by the casing c.

20 The casing c is perforated to allow the free passage of air to the burner and to allow it to flow through the same into the drum.

My improved gas-stove is economical in construction and is strong and durable. The 25 drum or body portion is so arranged that the heat from the burner is not delivered directly thereon, so that its finish is not quickly destroyed.

I have illustrated and described my improved gas-stove in detail in the form preferred by me. I am aware, however, that it is capable of considerable structural variation without departing from my invention.

Having thus described my invention, what 30 I claim as new, and desire to secure by Letters Patent, is—

1. In a gas-stove, the combination of a base having an upwardly-projecting flange thereon; a cross-piece on said base; a base-plate arranged on said cross-piece; a burner; a burner-tube having a supporting-flange thereon arranged through said cross-piece; an open-ended burner-casing arranged on the said flange on said base; a drum-like body, having a diameter exceeding that of the burner-casing and overhanging the upper end thereof, consisting of a barrel-like portion; a top having a downwardly-projecting flange on which the upper end of the said barrel is arranged; an 40 outwardly and downwardly projecting bottom rim, having an upwardly-projecting flange on which the upper end of said barrel is arranged; a lid for said top; a removable cap for said top for affording access to said lid; and supporting-standards for said body, having suitable offsets therein to adapt them to fit within the same and said burner-casing arranged to secure the parts thereof together and to said base, said standards being secured to the said 45 base, said flanges of said top, bottom rim, and base, and to said burner-casing at its upper end, for the purpose specified.

2. In a gas-stove, the combination of a base having an upwardly-projecting flange thereon; 50 a cross-piece on said base; a base-plate ar-

ranged on said cross-piece; a burner; a burner-tube having a supporting-flange thereon arranged through said cross-piece; an open-ended burner-casing arranged on the said flange on said base; a drum-like body, having a diameter exceeding that of the burner-casing and overhanging the upper end thereof, consisting of a barrel-like portion; a top having a downwardly-projecting flange on which the upper end of the said barrel is arranged; an 55 outwardly and downwardly projecting bottom rim, having an upwardly-projecting flange on which the upper end of said barrel is arranged; and supporting-standards for said body, having suitable offsets therein to adapt them to fit within the same and said burner-casing arranged to secure the parts thereof together and to said base, said standards being secured to the said flanges of said top, bottom rim, and base, and to said burner-casing at its upper end, for the purpose specified.

3. In a gas-stove, the combination of a base having an upwardly-projecting flange thereon; a burner; an open-ended burner-casing arranged on the said flange on said base; a drum-like body, having a diameter exceeding that of the burner-casing and overhanging the upper end thereof, consisting of a barrel-like portion; a top having a downwardly-projecting flange on which the upper end of the said barrel is arranged; an outwardly and downwardly projecting bottom rim, having an upwardly-projecting flange on which the upper end of said barrel is arranged; a lid for said top; a removable cap for said top for affording access to said lid; and supporting-standards for said body, having suitable offsets therein to adapt them to fit within the same and said burner-casing arranged to secure the parts thereof together and to said base, said standards being secured to the said flanges of said top, bottom rim, and base and to said burner-casing at its upper end, for the purpose specified.

4. In a gas-stove, the combination of a base having an upwardly-projecting flange thereon; a burner; an open-ended burner-casing arranged on the said flange on said base; a drum-like body, having a diameter exceeding that of the burner-casing and overhanging the upper end thereof, consisting of a barrel-like portion; a top having a downwardly-projecting flange on which the upper end of the said barrel is arranged; an outwardly and downwardly projecting bottom rim, having an upwardly-projecting flange on which the upper end of said barrel is arranged; and supporting-standards for said body, having suitable offsets therein to adapt them to fit within the same and said burner-casing arranged to secure the parts thereof together and to said base, said standards being secured to the said flanges of said top, bottom rim, and base, and to the said burner-casing at its upper end, for the purpose specified.

5. In a gas-stove, the combination of a base, having an upwardly-projecting flange thereon; a cross-piece on said base; a base-plate arranged on said cross-piece; a burner; a burner-tube having a supporting-flange thereon arranged through said cross-piece; an open-ended burner-casing arranged on the said flange on said base; a drum-like body, having a diameter exceeding that of the burner-casing and overhanging the upper end thereof, consisting of a barrel-like portion; a top having a downwardly-projecting flange on which the upper end of the said barrel is arranged; an outwardly and downwardly projecting bottom rim, having an upwardly-projecting flange on which the upper end of said barrel is arranged; a lid for said top; a removable cap for said top for affording access to said lid; and supporting-standards for said body, for the purpose specified.

6. In a gas-stove, the combination of a base having an upwardly-projecting flange thereon; a cross-piece on said base; a base-plate arranged on said cross-piece; a burner; a burner-tube having a supporting-flange thereon arranged through said cross-piece; an open-ended burner-casing arranged on the said flange on said base; a drum-like body, having a diameter exceeding that of the burner-casing and overhanging the upper end thereof, consisting of a barrel-like portion; a top having a downwardly-projecting flange on which the upper end of the said barrel is arranged; an outwardly and downwardly projecting bottom rim, having an upwardly-projecting flange on which the upper end of said barrel is arranged; and supporting-standards for said body, for the purpose specified.

7. In a gas-stove, the combination of a base having an upwardly-projecting flange thereon; a burner; an open-ended burner-casing arranged on the said flange on said base; a drum-like body, having a diameter exceeding that of the burner-casing and overhanging the upper end thereof, consisting of a barrel-like portion; a top having a downwardly-projecting flange on which the upper end of the said barrel is arranged; an outwardly and downwardly projecting bottom rim, having an upwardly-projecting flange on which the upper end of said barrel is arranged; a lid for said top; a removable cap for said top for affording access to said lid; and supporting-standards for said body, for the purpose specified.

8. In a gas-stove, the combination of a base having an upwardly-projecting flange thereon; a burner; an open-ended burner-casing arranged on the said flange on said base; a drum-like body, having a diameter exceeding that of the burner-casing and overhanging the upper end thereof, consisting of a barrel-like portion; a top having a downwardly-projecting flange on which the upper end of the said barrel is arranged; an outwardly and

downwardly projecting bottom rim, having an upwardly-projecting flange on which the upper end of said barrel is arranged; and supporting-standards for said body, for the purpose specified.

9. In a gas-stove, the combination of a base; a cross-piece on said base; a base-plate arranged on said cross-piece; a burner; a burner-tube having a supporting-flange thereon arranged through said cross-piece; an open-ended burner-casing; a drum-like body, open at its lower end, having a diameter exceeding that of the burner-casing, consisting of a barrel-like portion; a top; an outwardly and downwardly projecting bottom rim; a lid for said top; a removable cap for said top for affording access to said lid; and supporting-standards for said body, having suitable offsets therein to adapt them to fit within the same and said burner-casing arranged to secure the parts thereof together and to said base, for the purpose specified.

10. In a gas-stove, the combination of a base; a cross-piece on said base; a base-plate arranged on said cross-piece; a burner; a burner-tube having a supporting-flange thereon arranged through said cross-piece; an open-ended burner-casing; a drum-like body, open at its lower end, having a diameter exceeding that of the burner-casing, consisting of a barrel-like portion; a top; an outwardly and downwardly projecting bottom rim, and supporting-standards for said body, having suitable offsets therein to adapt them to fit within the same and said burner-casing arranged to secure the parts thereof together and to said base, for the purpose specified.

11. In a gas-stove, the combination of a base; a burner; an open-ended burner-casing; a drum-like body open at its lower end, having a diameter exceeding that of the burner-casing, consisting of a barrel-like portion; a top; an outwardly and downwardly projecting bottom rim; a lid for said top; a removable cap for said top for affording access to said lid; and supporting-standards for said body, having offsets therein to adapt them to fit within the same and said burner-casing arranged to secure the parts thereof together and to said base, for the purpose specified.

12. In a gas-stove, the combination of a base; a burner; an open-ended burner-casing; a drum-like body open at its lower end, having a diameter exceeding that of the burner-casing, consisting of a barrel-like portion; a top; an outwardly and downwardly projecting bottom rim; and supporting-standards for said body, having suitable offsets therein to adapt them to fit within the same and said burner-casing arranged to secure the parts thereof together and to said base, for the purpose specified.

13. In a gas-stove, the combination of a base; a cross-piece on said base; a base-plate arranged on said cross-piece; a burner; a burner-

- tube having a supporting-flange thereon arranged through said cross-piece; an open-ended burner-casing; a drum-like body; open at its lower end, having a diameter exceeding 5 that of the burner-casing, consisting of a barrel-like portion; a top; an outwardly and downwardly projecting bottom rim; a lid for said top; a removable cap for said top for affording access to said lid; and supporting- 10 standards for said body, for the purpose specified.
14. In a gas-stove, the combination of a base, a cross-piece on said base; a base-plate arranged on said cross-piece; a burner; a burner- 15 tube having a supporting-flange thereon arranged through said cross-piece; an open-ended burner-casing; a drum-like body open at its lower end, having a diameter exceeding that of the burner-casing, consisting of a barrel- 20 like portion; a top; an outwardly and downwardly projecting bottom rim; and supporting-standards for said body, for the purpose specified.
15. In a gas-stove, the combination of a base; 25 a burner; an open-ended burner-casing; a drum-like body open at its lower end, having a diameter exceeding that of the burner-casing, consisting of a barrel-like portion; a top; an outwardly and downwardly projecting bot-
- tom rim; a lid for said top; a removable cap 30 for said top for affording access to said lid; and supporting-standards for said body, for the purpose specified.
16. In a gas-stove, the combination of a base; a burner; an open-ended burner-casing; a 35 drum-like body open at its lower end, having a diameter exceeding that of the burner-casing, consisting of a barrel-like portion; a top; an outwardly and downwardly projecting bottom rim; and supporting-standards for said 40 body, for the purpose specified.
17. In a gas-stove, the combination of a base; a cross-piece on said base; a base-plate arranged on said cross-piece; a burner; a burner- 45 tube having a supporting-flange thereon arranged through said cross-piece; an open-ended burner-casing on said base; a drum-like body open only at its lower end, having a diameter exceeding that of the burner-casing; and supports for said body, for the pur- 50 pose specified.

In witness whereof I have hereunto set my hand and seal in the presence of two witnesses.

HENRY J. BRESSON. [L. S.]
